UNITED STATES PATENT OFFICE.

FRANCIS CHARLES SOUTHARD AND HENRY GEORGE SOUTHARD, OF SOUTHAMPTON,
ENGLAND.

MACHINE FOR ROLLING IN THE BASE-PLATES OF HIGH-EXPLOSIVE SHELLS AND SUCH
LIKE.

1,352,321.

Specification of Letters Patent.

Patented Sept. 7, 1920.

Application filed August 15, 1918. Serial No. 249,965.

To all whom it may concern:

Be it known that we, FRANCIS CHARLES SOUTHARD and HENRY GEORGE SOUTHARD, engineers, subjects of the King of Great Britain, residing at 15 Bellevue Terrace, in the county borough of Southampton, Hants, England, have invented certain new and useful Improvements in Machines for Rolling in the Base-Plates of High-Explosive Shells 10 and Such like, of which the following is a specification.

This invention relates to improved means and apparatus for fixing in the base plates of high explosive shells by means of rolling, 15 and can be worked by pulley or gear drive as may be convenient.

To this end we employ a bed plate or stand to which are fixed bearings and shaft; to the said shaft is fitted a hardened steel roller; 20 also the pulley or driving gear, so that when the pulley or gear is revolved it causes the roller to turn also.

Means are also provided whereby two shells can be forced, base foremost, on to two 25 opposite sides of the revolving roller.

Journal and thrust bearings are provided for the shells, so that they are free to revolve on their axes under the action of the roller, and that they may be easily inserted and extracted. 30 The driving roller may be either smooth or corrugated to any suitable form for the purpose.

Other roller or rollers may be provided of suitable form and in suitable positions to 35 finish off the rolling process and oppose the thrust of the driving roller.

Means are also provided whereby the roller or rollers can be adjusted laterally across the base of the shell to bring them in the most 40 convenient position for working.

Having thus generally described the object and nature of the invention, we will now proceed to describe it with reference to the accompanying drawings, which are marked 45 with letters and figures of reference corresponding with those used in the following explanation.

In the drawings:—

Figure 1 is an end elevation, Fig. 2 a side 50 elevation, Fig. 3 a plan view, and Figs. 4, 5 and 6 details of the apparatus. Figs. 7 and 8 are longitudinal sections showing one of the forms of shell on which the apparatus is adapted to operate.

With reference to the drawings, A designates the bed plate which is supported on the frame B, and C, C denote the shell holders which are pivotally fixed on the centers D, D. The shell holders C, C are provided with roller bearings E, E, and with thrust 60 bearings at F, F. The shell holders C, C are so mounted on the bed plate A as to be capable of swinging outward as shown in Fig. 3, and to provide for inserting and removing the shells L. They are swung back against 65 the adjustable stops G, G, and retained by two spring latches H, H. These latches are pulled downward by means of a foot pedal H' when it is desired to swing out the shell holders C, C. The holders C, C are prevented from rising off the bed plate by lugs I, I carried by adjustable stops G, G. The thrust bearings F, F, are capable of sliding axially by means of the action of the levers K, K, thus causing the shells L, L to approach and 70 press upon the roller M. L' designates the base plates adapted to be rolled into the head of the shell L. Motion is given to the levers K, K by the levers N, N and tension rods O, O. The pressure applying lever T is 75 mounted on and turns, a shaft U journaled in a suitable bracket U'. The lever N is eccentrically mounted relative to shaft U on a shaft or pin S (Figs. 5 and 6). When hand lever T is actuated in one direction lever N 80 is moved to the dotted line position indicated in Fig. 5. This results in movement outward of the rods O and raises weighted arm Q, thus placing levers K under action of the weight P with the result that the head of the 85 lever K is forced inward against the shell holders. By this means a most even feeding of the work to the tool is effected under action of weighted rod Q.

The action of moving the fulcrum of the 90 lever N nearer to the lever K has the effect of reacting on the weight P and raising it from its lower or resting position so that it exerts its pressure which is multiplied by the system of levers and tension rods before 95 mentioned.

Equal pressure upon the two shells is assured by the fulcrum V of the lever Q being free to slide in the slot W. The roller M (which is grooved in the center to obviate 100 the risk of obliterating any stamp on the base of the shell, and is reversible so that when one side is worn out it can be turned

over and the unused part brought into action) is mounted upon a shaft X, which is caused to revolve in a bearing Y by the pulley Z, and the thrust of the roller is taken by the bearing 2. The bearing Y is adjustable laterally by the hand wheel 3 and the screw 4, and its travel is limited by projection 5^a of the bearing Y and screw adjusted limit stops 5. Although specially designed for 18 Pdr. high explosive, it will be seen to be equally suitable for any shell requiring a base plate.

In operation, the shell holder or holders, C or C, C, are turned outward on their centers D and the shell or shells L or L, L are inserted, the base plates L' having first been placed in position in the shells and held in position by springs 6, 6, which are turned out as shown in Figs. 1 and 4 so as to remove or replace the shells in the bearings E. The holders with the inserted shells are then swung back against the stops G, G and retained by the latches H, H and caused to slide axially and to approach and press upon the roller M. As before stated, motion is given to the levers K, K by the levers N, N and tension rods O, O, which are actuated by the weight P. Equal pressure upon the two shells is assured by the fulcrum V of the lever Q being free to slide in the slot W. The roller M is then put in action by means of the pulley Z and rolls in the base plates of the shells.

Having thus described our invention, what we claim as new therein, and desire to secure by Letters Patent is:—

1. In a machine for rolling in base plates for explosive shells, a base portion, a rolling tool mounted on said base portion, means to move said rolling tool transversely of said base, means to limit such transverse movement, shell holders pivotally secured to said base and adapted to be swung outward relative to said base, adjustable means for positioning said shell holders on said base, means to retain said shell holders in position on said base, means to release said shell holders from operative position on said base and automatically operable means for moving said shell holders to operating position relative to said rolling tool.

2. In a machine for rolling in base plates for explosive shells, a base portion, a rolling tool mounted on said base portion, means to move said rolling tool transversely of said base, means to limit such transverse movement, shell holders pivotally secured to said base and adapted to be swung outward relative to the base, adjustable means for positioning said shell holders on said base, means to retain said shell holders in position on said base, means to release said shell holders from operating position on said base, automatically operable means for moving said shell holders to

operating position relative to said rolling tool, and means carried by said shell holders for retaining the base plates of shells to be operated on in position.

3. In a machine for rolling in base plates for explosive shells, a base portion, a metal rolling tool revolvably mounted in a tool holder on said base, means to move said tool holder transversely of said base, adjustable means to limit such transverse movement, shell holders slidably mounted and pivotally secured to said base, adjustable means for positioning said shell holders on said base, spring-pressed means for retaining said shell holders in position on said base, manually operable means to release said shell holders from position, and automatically operable means for moving said shell holders to operating position relative to said rolling tool.

4. In a machine for rolling in base plates for explosive shells, a base portion, a rolling tool mounted on said base, manually operable means to move said rolling tool transversely of said base, means to limit such transverse movement, shell holders pivotally secured to said base, means for positioning said shell holders on said base, means to retain said shell holders in position on said base, automatically operable means comprising a weighted lever and connected operating arms for moving said shell holders to operating position relative to said rolling tool.

5. In a machine for rolling in base plates for explosive shells, a base portion, a tool holder slidably mounted on said base portion, means to move said tool holder relative to said base, a metal rolling tool mounted in said tool holder, adjustable means to limit the movement of said tool holder relative to said base, a shell holder comprising a shell head-receiving portion, and a shell body-receiving portion adapted to surround a shell and having disposed therein bearings, a roller positioned at one end of said shell holder, and means to move said shell holder longitudinally of said base.

6. In a machine for rolling in base plates for explosive shells, a base portion, a tool holder slidably mounted on said base portion, means to move said tool holder relative to said base, a metal rolling tool mounted in said tool holder, adjustable means to limit the movement of said tool holder relative to said base, a shell holder comprising a shell head-receiving portion, and a shell body-receiving portion adapted to surround a shell and having disposed therein roller bearings, a roller positioned at one end of said shell holder, and means including a lever arm pivoted to said base and co-acting with said roller to move said shell holder longitudinally of said base.

7. In a machine for rolling in base plates

for explosive shells, a base portion, a tool holder slidably mounted on said base portion, means to move said tool holder relative to said base portion, a metal rolling 5 tool mounted in said tool holder, adjustable means to limit the movement of said tool holder relative to said base, a shell holder comprising a shell head-receiving portion having thrust bearings therein and a shell 10 body-receiving portion adapted to surround a shell and having therein roller bearings, a roller positioned at one end of said shell

holder, and means comprising a plurality of levers pivoted to said base at different points to move said shell holder longitudinally of said base. 15

In testimony whereof we have hereunto set our hands in presence of two subscribing witnesses.
